UNITED STATES PATENT OFFICE.

JOSEPH ERNST FLETCHER, OF DUDLEY, ENGLAND.

HEATING OR CIRCULATION OF STEAM-GENERATORS.

1,032,197.

Specification of Letters Patent.

Patented July 9, 1912.

Application filed February 15, 1912. Serial No. 677,806.

To all whom it may concern:

Be it known that I, JOSEPH ERNST FLETCHER, a subject of the King of England, residing at Dudley, in the county of Worcester, England, have invented certain new and useful Improvements in or Connected with the Heating or Circulation of Steam-Generators, of which the following is a specification.

10 This invention has reference primarily to the heating of "feed-water" supplied to steam generating plant, comprising a battery or group of steam generators, wherein all of the feed water supplied to the plant is 15 heated in one steam generator of the battery or group (or in more than one of them) to, at least, the temperature corresponding with the pressure of the steam to be generated, and steam is also generated from it, 20 and it is then delivered or distributed to the other generator or generators of the group or battery at this temperature.

It relates, however, also to other cases of steam generating plant, where it is desired to heat the feed water by the heat of "live" steam.

The object of the invention is primarily to render the efficiency, generally, of the feed steam generator or generators of steam 30 generating plant of the kind more particularly referred to above, higher; and thereby enhance the efficiency of the power plant according to this system, as a whole. And it may be assumed, in the description of the 35 invention, that the steam generator referred to in it, is the feed steam generator of such a plant; although it is to be understood, that the mode of or means for heating feed water hereafter described, may be applied 40 and used in connection with steam generators or steam generating plant, which are or is not according to that system and that where this mode or means can be advantageously so applied or used, such use 45 or application is to be assumed to be covered under this invention and application for patent.

The invention will be described in connection with the accompanying drawings, in 50 which it is illustrated in several applications.

In these drawings, Figure 1 shows diagrammatically a steam generator of the "Lancashire" type, fitted with the apparatus; Fig. 2 shows it applied to a steam generator of the "water tube" type; and Fig.

3 shows it applied to a generator of the locomotive type. Fig. 4 is a view showing a part of the apparatus, in longitudinal section.

In the introduction of feed water to the steam generator according to this invention, there is imparted or given to it, the effect of the "ejector-condenser"; that is, the water as it enters the generator is passed through nozzles or the like, to which the steam of the generator—but not the hot water in it—has access; with the effect that the inter-action between the relatively cool water entering, and passing through the apparatus, and the steam at the temperature of generation introduced from the steam space of the generator, imparts a large increment of heat to the water, and also promotes an increase in its velocity; and this 70 water so heated and in flow, is conducted and delivered into the water of the generator, and in the direction of the true convection currents, and so assists them.

Referring now to the drawings, 1 is the steam generator, or part of the steam generator, as the case may be, in which the apparatus is fitted.

2 is the casing or body of or the part of the apparatus containing nozzles or the like, 85 through which water and steam pass as above described.

3 is the feed water inlet conduit to the apparatus, which is introduced at one end of the casing 2; 4 is the steam inlet conduit, 90 which enters casing 2 at the side; and 5 is the hot water outlet, which is at the end of the casing 2 opposite to the inlet 3.

In the particular form or arrangement of nozzle apparatus shown in Fig. 4, the casing 95 2 has within it a plurality of nozzles 6 on a common axis, and one which is coincident with those of the inlets and outlets 3, 5. The water, which say is delivered to the apparatus by a pump at the required velocity, 100 leaves the end of the inlet branch 3 inside the casing 2 as a jet, and discharges direct into the relatively large inlet of the first cone or nozzle 6; and the steam existing in the casing 2 (to which it has been conducted by the pipe 4 from the live steam space of the generator) has access to and acts on the water passing from the inlet 3 to the nozzle, at the annular space existing between the ends of these parts. And, likewise, as it 110 passes in a jet from the first cone to the second, and so on, the steam has access to it on

the different spaces or parts where the discharge ends of the cones or nozzles are disposed over the inlets of this subsequent nozzle or cone; and so the water is acted on 5 by it due to the different temperatures of it and the steam, and it becomes heated thereby rapidly, and absorbs into itself a large quantity of heat. That is, in other words, it receives the heating effect which the water 10 receives in an "ejector-condenser," and has its general effect, and action.

The hot water as discharged, is conducted through the pipe 5 in the direction of the true convection currents of the water in the 15 generator. That is, in the case of a generator of the type shown in Fig. 1, this water is delivered into the bottom of the generator, and delivered in the direction toward the hotter part, viz: toward the furnace, from a cooler part of the generator; while in the case of the water tube steam 20 generator shown in Fig. 2, it is delivered into the water in the steam drum 1, and directed toward that end where the water 25 passes down from this drum to the heating tubes. Similarly, in Fig. 3, the apparatus is placed in the water space of the locomotive boiler above the tubes, and delivered in a direction toward the crown of the fire-box. 30 By placing the apparatus, and using it in the manner described, it is kept free from all contractual strains, and from the strains set up by "water hammer;" while the supply of steam to it is effected without the use 35 of a valve.

While it has been stated that the steam supply to the incoming water is that existing in the steam space of the generator and is at the temperature of saturation at the 40 pressure existing, yet in some cases, the steam may be super-heated and may be that of, and from the generator itself after having passed through a super-heater, or supplied from a separate source.

45 What I claim is:—

1. In combination, a steam generator; a nozzle apparatus of the ejector condenser type placed in the water of the steam generator, and through which the water to be 50 fed to the boiler and heated is passed; a conduit connecting the case of the apparatus

with the steam space of the generator; a conduit connected with the casing of the apparatus adapted to supply the water to be heated to it; and a conduit connected with the casing of the apparatus, and adapted to deliver the heated water in the direction of the true convection currents thereof; substantially as described.

2. In combination, a steam generator, a 60 casing inclosed in the generator and submerged in the water therein, a steam inlet pipe communicating with the casing and the steam space in the generator, a water inlet pipe communicating with one end of the casing, the outlet end of said water inlet pipe having a nozzle which projects into the casing, a water outlet nozzle extending from the opposite end of the casing in alinement with the water inlet pipe and a plurality of 65 spaced apart nozzles in the casing between the water inlet and outlet nozzles.

3. In combination, a steam generator, a casing inclosed in the generator, and submerged in the water therein, a steam inlet 75 pipe communicating with the casing and the steam space in the generator, a water inlet pipe communicating with one end of the casing, the outlet end of said water inlet pipe having a nozzle which projects into 80 the casing, a water outlet nozzle extending from the opposite end of the casing in alinement with the water inlet pipe and a plurality of spaced apart nozzles arranged in alinement with the water inlet and outlet 85 nozzles.

4. In combination, a steam generator, a plurality of alined spaced apart nozzles through which water passes to the generator, and means for supplying steam to the 90 spaces between the nozzles to be drawn therethrough by the force of the water, whereby to preheat the water before delivery to the generator.

In testimony whereof I have signed my 95 name to this specification in the presence of two subscribing witnesses.

JOSEPH ERNST FLETCHER.
